US0D1006383S

(12) **United States Design Patent** (10) Patent No.: **US D1,006,383 S**
Abdul Rahman et al. (45) Date of Patent: **** Nov. 28, 2023**

(54) **MOBILE CART WITH SHELVES**(71) Applicant: **AMQ Solutions, LLC**, Santa Clara, CA (US)(72) Inventors: **Abdul Azim Abdul Rahman**, Selangor (MY); **Han Seb Hong**, Milpitas, CA (US); **Ng Shin Tee**, Selangor (MY)(73) Assignee: **AMQ Solutions, LLC**, Santa Clara, CA (US)(**) Term: **15 Years**(21) Appl. No.: **29/803,776**(22) Filed: **Aug. 16, 2021**(51) LOC (14) Cl. **12-02**

(52) U.S. Cl.

Primary Examiner — Cynthia Ramirez*Assistant Examiner* — Tamara L Hahn(74) *Attorney, Agent, or Firm* — Crowell & Moring LLP(57) **CLAIM**

The ornamental design for a mobile cart with shelves, as shown and described.

DESCRIPTION

FIG. 1 is a top front, right perspective view of the mobile cart with shelves;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom/left perspective view thereof.
